UNITED STATES PATENT OFFICE.

JOHN SKINDERVIKEN, OF CHICAGO, ILLINOIS, ASSIGNOR OF ONE-HALF TO OLAF E. RAY,
OF CHICAGO, ILLINOIS.

HAT-FASTENER.

1,288,714.

Specification of Letters Patent. Patented Dec. 24, 1918.

Application filed April 24, 1918. Serial No. 230,482.

To all whom it may concern:

Be it known that I, JOHN SKINDERVIKEN, a subject of the King of Norway, having declared my intention to become a citizen of the United States, residing at Chicago, in the county of Cook and State of Illinois, have invented certain new and useful Improvements in Hat-Fasteners, of which the following is a specification.

10 My invention relates to a hat fastener and its main object is to provide novel fastening means with hair-gripping members movable relatively to each other and operable by a means common to each of the 15 members.

Also I aim to provide an article of this kind which is capable of being removably attached to practically every style of hat without destroying the appearance thereof; 20 one in which the operating means is movable and has a novel fastening member to cooperate with its mounting means to fasten the operating means in closed position and prevent accidental displacement from open 25 position; and to provide the specific construction hereinafter described and illustrated in the accompanying drawings. Servient objects and advantages will appear as the description progresses.

30 In the accompanying drawings illustrating the present preferred embodiment:—

Figure 1 is an elevation of a hat, partly broken away, showing the application of my improvement thereto;

35 Fig. 2 is a cross sectional view taken substantially on the line 2—2 of Fig. 1;

Fig. 3 is an enlarged side elevation of the fastening means, applied to a hat fragment and partly broken away;

40 Fig. 4 is a cross sectional view on the line 4—4 of Fig. 3 but showing the fastening means only;

Fig. 5 is a detail view, fragmentarily shown partly in side elevation and partly in 45 section of a modified form;

Fig. 6 is a view principally in vertical section, illustrating a further modified form and;

Fig. 7 is a top view of the form shown in 50 Fig. 6.

Referring specifically to the drawings, the device in Fig. 1 has been shown applied to a conventional form of ladies' hat at 8. The improvements are preferably disposed centrally of the hat and removably secured to

the crown 9. To this end, a mounting means is employed consisting of a disk or hub 10 which underlaps the crown and has a central sleeve 11 extending upwardly therethrough and above it receiving a nut 12, threaded to 60 the exterior thereof and adapted to be clamped against the crown. This mounting means in view of this construction, can be applied to practically every style of hat without injuring it or destroying its ornamental 65 appearance.

A plurality of fastening tines 13 preferably curved inwardly at their free ends as at 14, are pivoted as at 15 to lugs or ears 16 integral with and depending from the disk 70 or hub 10.

A suitable actuating means to move the tines 13 relatively is provided and may consist of a post or rod 17 and radiating, preferably curved, arms 18 at the bottom end, 75 mounting pins or pivots 19 which extend through elongated slots 20 in the tines.

Before the hat is fastened, the fastening device is in the position shown in Figs. 1 and 3. It is held in this position by means of a 80 leafspring 21 suitably fastened to the post and being tensioned to spring outwardly from the center thereof. In this way, the spring frictionally exerts pressure against the bore of the sleeve and holds the tines in 85 open position against accidental closing.

The head 13 and post 17 are adapted to be depressed so as to move the tines to the closed position shown in Fig. 2. This leafspring 21 is adapted to fasten the parts in 90 closed position and to this end is provided with a projection or shoulder 22 to underlap the disk 10 as shown in Fig. 2. A manipulating portion for this spring is provided at 23 whereby it may be moved toward the 95 center of the post so that the shoulder 22 may disengage the disk. To facilitate this movement, a slot or recess 24 is cut in the post.

In operation, with the parts shown in the 100 position of Figs. 1 and 3, the hat is placed upon the head of the wearer and the head 13 and portion 23 grasped. Slight pressure of the fingers moves the spring 21 inwardly so that the post may be more easily depressed. By depressing the post, the tines 13 move from the pivots 15 through the action of the arms 18 and pins 19 into penetrating engagement with the hair of the 105 wearer. In closed position, the parts are as 110

in Fig. 2, where the lug or shoulder 22 clips into underlapping relation with the disk 10. In removing the hat, the part 23 is again moved relative to the post 17 and head 13, 5 so as to move the shoulder 22 from engagement with the disk whereupon the post can be drawn upwardly and the tines spread to the position of Fig. 3, to disengage the hair.

Since changes in the details of construction 10 may be resorted to, I do not limit myself to the precise form shown.

One of the modifications which may be used is illustrated in Fig. 5. In this figure, the equivalent of disk 10 is shown at 30, 15 preferably being greater in diameter, and having the tines, the equivalent of tines 18, at 31, pivoted to the disk 30 at 32. Post 33 is the equivalent of post 17 and to this post links 34 are pivoted at 35, and then individually to the tines at 36. With this form, 20 it will be seen that movement of the post 33 will move the tines 31 through the medium of the links 34.

The further modification illustrated in 25 Figs. 6 and 7 may consist of a plate 40 having openings 41 through which fastening means to secure it to a hat, may be passed. A central enlarged opening is provided at 42, which is spanned by a pin 43 mounted on 30 the plate and on which tines 44 are pivoted for relative movement. These tines preferably are corrugated at 45 to increase their efficiency in engaging the hair. A spring, substantially U-shaped, is provided at 46 35 and fastened to the manipulating portions 47 of the tines 44. This spring serves to urge the portions 45 together. In fastening this form to the hair, the portions 47 are moved relatively to each other so as to 40 spread the tines 44, after which they are brought into engagement with the hair, and released, so that the spring 46 will force the tines 44, at 45, into relatively close relation.

I claim:

- 45 1. A fastening device having a hub, means to mount the hub, a sleeve extending from the hub, actuating means slidable through the hub, a movement-retarding means extending from the actuating means through 50 the sleeve and being frictionally engageable with the interior of the sleeve, fastening means extending from the hub, and means to operate the fastening means through movement of the actuating means.
- 55 2. A fastening device having a hub, means to mount the hub, a sleeve extending from

the hub, actuating means slidable through the hub, a movement-retarding means extending from the actuating means through the sleeve and frictionally engageable with 60 the interior of the hub, the last mentioned means having a shoulder to underlap the hub and being tensioned to move away from the actuating means, and fastening means operable through movement of the actuating 65 means.

3. A fastening device having a hub member provided with a sleeve to extend through a hat, a nut threaded to the sleeve and engageable with the hat on the opposite side 70 thereof to the hub member, fastening means extending from one of said members, and means to operate said members disposed in said sleeve.

4. A fastening device having a hub provided with a disk engaging one side of the crown of the hat, a sleeve extending from said disk and extending through the hat, a nut threaded to said sleeve engaging the crown of the hat on the other side, lugs depending from the disk, tines pivoted to said lugs, a post disposed in said sleeve, arms extending from the post, means connecting said arms to the tines to move the tines through movement of the post, a spring extending 80 from the post and through said sleeve and tensioned to move away from the post to frictionally engage the interior of the sleeve, said spring having a shoulder to underlap said disk and having a finger piece, and said 90 post having a recess to accommodate movement of the spring toward the center of the post.

5. A fastening device having a hub, means to mount the hub, a sleeve extending from the hub, an actuating post slidable through the hub, a spring extending from the post fastened to the sleeve tensioned to move away from the post having a shoulder to underlap the hub, said spring having a finger piece, and said post having a recess into 100 which said spring may be pressed, a fastening means extending from the hub, and means to operate the fastening means through movement of the actuating means. 105

In testimony whereof, I have affixed my signature in the presence of two witnesses.

JOHN SKINDERVIKEN.
